UNITED STATES PATENT OFFICE.

THOMAS G. KUS, OF CHICAGO, ILLINOIS, ASSIGNOR, BY MESNE ASSIGNMENTS, TO
CHICAGO TRUST COMPANY, TRUSTEE, OF CHICAGO, ILLINOIS, A CORPORATION.

COKE OVEN.

Application filed July 18, 1923. Serial No. 651,693.

My invention relates to by-product coke ovens, which are commonly built in benches or batteries containing a large number of coking chambers extending transversely 5 through the bench or common construction and externally heated by hot gases formed in and circulating through passages or flues formed in the walls separating adjacent chambers. In certain respects which 10 will be hereinafter pointed out the present invention is in the nature of an improvement in the coke oven construction disclosed in an application filed by me October 4, 1919, Serial No. 328,537. In that construction the walls are formed with vertical 15 heating flues, provision being made to supply fuel gas and air to support combustion alternately at the top and bottom of the flues so that the flow of heating gases is 20 alternately upward and downward. The air is preheated by passing through regenerators formed in the foundation beneath the ovens, alternate regenerators supplying 25 air to the lower ends of the combustion flues and intermediate regenerators supplying the upper ends of the flues according to the direction of operation at the time. When air is passing through regenerators 30 of one set, the regenerators of the other are being heated by the waste heating gases, the regenerators having valved connections by which alternately air is admitted thereto and products of combustion drawn therefrom. In another aspect of my present 35 invention it may be considered an improvement in the so-called flueless or Roberts type of oven which is characterized by broad heating chambers extending substantially the length of the coke ovens, an example of 40 which may be found in my application for patent, Serial No. 364,109, filed by me March 8, 1920.

The present invention provides a more uniform and efficient distribution of heat to 45 the charges within the coking chambers, whereby the coking thereof is more rapidly effected and a better and more uniform grade of coke produced, and coals heretofore considered unadapted for the production of 50 metallurgical coking is available for that purpose.

In my improved construction the advantages of the flueless type of oven with its 55 vertical flow of heating gases and substantially uninterrupted heat-absorbing surface

extending from end to end of the coking chambers is combined with that of reversal of flow by which the heat absorbed from the gases is evenly distributed between the upper and lower portions of the wall. Furthermore, the distribution of heat longitudinally of the ovens is controlled and made substantially uniform by supplying the ignition chambers or points of combustion arranged along the top and bottom of the heating spaces or chambers of the wall independently with fuel gas and air to support combustion, the regenerators being subdivided for this purpose so that each subdivision independently supplies a small number of air ports only. Furthermore, lateral drift of the products of combustion due to atmospheric or other causes which would cause unequal heating longitudinally of the wall is substantially prevented by thin vertical diaphragms arranged at suitable intervals which substantially confine the heating gases to a vertical course of travel without, however, being of sufficient thickness to materially affect the even distribution of heat to the surfaces of the wall in contact with the contents of the coking chambers. Other features and advantages of my invention will appear from the drawings accompanying and forming a part of the specification and the detailed description thereof herein- 60 after. It is to be understood however that the specific disclosure is for the purpose of exemplification only and that the scope of the invention is defined in the following claims, it being my intention to claim it as broadly as the prior art will permit.

In the drawings Figs. 1, 2 and 3 are vertical transverse sections partly through a bench or battery of ovens embodying my invention, Fig. 1 being taken on the planes of the broken line 1-1 of Fig. 4, looking in the direction of the arrows, Fig. 2 on the broken line 2-2 of Fig. 4, looking in the direction of the arrows, and Fig. 3 on the broken line 3-3 of Fig. 6, looking in the direction of the arrows; Figs. 4, 5, 6 and 7 are fragmentary, vertical, longitudinal sections showing two complete units of the bank or battery, Fig. 4 being on the plane of the line 4-4 of Fig. 3, looking in the direction of the arrows, Fig. 5 on the plane of the line 5-5 of Fig. 3, looking in the direction of the arrows, Fig. 6 on the plane of the line 6-6 of Fig. 3, looking in the di- 65 70 75 80 85 90 95 100 105 110

- rection of the arrows, and Fig. 7 on the plane of the line 7—7 of Fig. 3, looking in the direction of the arrows; Figs. 8, 9, 10, 11 are horizontal sections looking downward, Figs. 8 and 9 showing a single heating wall only, Fig. 8 being on the plane of the line 8—8 of Fig. 4, Fig. 9 on the plane of the line 9—9 of Fig. 4, Fig. 10 on the broken line 10—10 of Fig. 4 and Fig. 11 on the plane of the line 11—11 of Fig. 3; Fig. 12 is a fragmentary vertical section on the same plane as Fig. 3. Each part is identified by the same reference character wherever it occurs throughout the several views.
- 18 The battery or bench of ovens may be composed of brickwork or of concrete construction and brickwork combined, as usual, the heating walls, or those portions thereof which comprise the heating or combustion chambers, being preferably formed of silica brick or other heat resistant material. The coking chambers 20 are formed in the upper part of the construction, the lower part being occupied by the regenerative chambers 21 for preheating the air supplied to the heating chambers in the walls intermediate the coking chambers. The coking chambers may be of usual dimensions but preferably are somewhat narrower and provided with the usual charging openings 21 and openings 22 at the ends thereof for the discharge of the coke.
- 19 Each intermediate or heating wall is formed with two series of heating chambers arranged respectively on opposite sides of the median plane thereof. The heating chambers comprise upper and lower ignition chambers or spaces 23, 24 and an intermediate heat absorption zone 25 across which last extend refractory heat absorbing elements 26. Preferably these elements are integral parts of brick of which they form the reduced waist or intermediate portions, the heads or ends 27 of which supplemented by intermediate courses of narrow brick 28, form the side walls of the heat absorbing chamber. The intermediate portion of the wall, in which the heat absorption zones are located, is composed of two outside courses of these dumbbell shaped brick and an intermediate course in which are formed certain ducts and flues which will presently be described.
- 20 The ignition chambers 23, 24 are evenly spaced along the top and bottom of the heating chambers and are in unobstructed communication with the heat absorption zones and separated from each other by webs 29, 30. Each ignition chamber is formed with a gas and an air port, the upper gas ports being shown at 31, the lower gas ports at 32, the upper air ports at 33 and the lower air ports at 34. From the gas ports 31 vertical ducts 35 formed in the brickwork lead to the top of the structure, see Figs. 2 and
- 6, where they are supplied with gas from mains 36 extending across the top of the furnace. The lower gas ports 32 open into vertical passages 39 with which vertical ducts 40 connect by inclined passages 41, see Fig. 7. The ducts 40 extend to the top of the structure where they are supplied with fuel gas from the mains 42 extending across the top of the structure, see Fig. 7. As seen in Figs. 7 and 8, the ducts 40 are formed in the brickwork intermediate the heating chambers and the brickwork or masonry above the same. Horizontal passages 43 extend transversely of the bench or battery of ovens directly beneath passages 39 with which they communicate through ports 44, see Fig. 7, said ports being normally closed by ball valves 45 of refractory material. The passages 43 are for the purpose of cleaning out the gas ducts and extend through the faces of the structure so as to be accessible for this purpose and when the dust is to be removed from the ducts 39, 40 it is only necessary to raise the valves 45, permit it to drop into the passages 43 and scrape it out of the latter by a suitable instrument.
- 21 In order to avoid too great a drop in the temperature of the gases in their travel through the combustion chambers I supply an excess of air to the ignition chambers in which combustion is taking place and supply additional fuel gas about midway of the heat-absorption zone which is consumed thereby. Thus also excessively high temperatures are avoided in the ignition chambers by the dilution of the products of combustion with the excess air. The intermediate fuel ports are shown at 46, see Figs. 2 and 6, which ports receive the gas from vertical ducts 47 likewise extending through the middle course of the wall to the top surface of the structure. These ducts are likewise supplied with fuel gas from the mains 42. The branch pipes 48 by which the gas ducts are supplied from the mains are preferably provided with individual valves as illustrated in Figs. 2 and 6, for controlling the supply of fuel gas, but the mains are also controlled by valves whereby the supply of gas may be turned into either the upper or the lower ignition chambers in reversing the operation.
- 22 The lower ignition chambers of the heating chambers on opposite sides of each oven are supplied with preheated air from the regenerator 49 immediately below said oven and the upper ignition chambers in each wall are supplied with preheated air from the regenerator 50 immediately beneath said wall. The heating chambers or spaces in the intermediate walls are divided longitudinally by thin diaphragms or partitions 51 at suitable intervals to guide the gases in a substantially vertical direction. In the par-

ticular construction disclosed each heating space is divided into six such chambers and the regenerators are similarly divided by walls 52 immediately beneath the dia-
 phragms 51. Thus the battery or bench of
 5 ovens is divided transversely as well as
 longitudinally into independent heating
 units, each pair of combustion chambers re-
 ceiving its supply of heated air from an
 10 independent regenerator unit. The regen-
 erator units are again subdivided into pairs
 of elements each of which supplies a small
 number of ignition chambers with air. In
 15 the specific construction shown each regen-
 erator unit is divided into four elements each
 of which supplies two ignition chambers,
 the elements of the respective units of re-
 generators 49 being marked respectively *e*,
 20 *f*, *g* and *h* and those of regenerator 50 be-
 ing marked respectively *a*, *b*, *c*, and *d*. Re-
 ferring to Figs. 3, 4, 5, it will be seen that
 flues 57 extend vertically in pairs from the
 25 respective elements *a*, *b*, *c*, *d* of regenerator
 50 through the heating walls and inter-
 mediate the heating chambers therein, one
 flue of each pair turning to the left, as seen
 in Fig. 4, at its upper end, and the other
 30 member of each pair turning to the right,
 as seen in Fig. 5 and each communicates
 with the air ports 33 in two adjacent upper
 ignition chambers through a horizontal pas-
 sage 50, see Fig. 2. The extent of opening
 35 of the ports 33 may be controlled by small
 pieces of brick 61 and for manipulating the
 latter a tapering chamber 62 opens through
 the upper face of the structure but is nor-
 mally closed.

As seen in Figs. 1, 2, 4, 5 and 10 the first
 40 and third elements *e*, *g*, of each unit of
 regenerators 49 are formed with short hori-
 zontal flues 63 extending to the right as
 viewed in Fig. 2, and the second and fourth
 elements *f*, *h* are formed with similar flues
 45 64 extending to the left, the flues 63, 64 be-
 ing in parallel planes as seen in Figs. 4 and
 10. The flues 63 are each connected by in-
 clined passages 65 with two of the air ports
 50 34 of the lower ignition chambers 24 to the
 left of the coke oven immediately above the
 same while the flues 64 are each similarly
 55 connected to two of the ignition chambers
 at the right of the coking chamber im-
 mediately above.

Each of the units of each of the regenera-
 60 tors is provided with an independent hori-
 zontal flue leading parallel to the regenera-
 tor through a side wall of the bench through
 which it alternately receives air and dis-
 charges waste gas. Each of the elements of
 65 such unit is open to said flue. In the par-
 ticular exemplification of the invention
 specifically disclosed there being six regen-
 erator units to each regenerator the flues
 from three of them lead to one side of the
 70 bench while the flues from the other three
 lead to the other side of the bench. While
 only one side of the bench is shown it will
 be understood that the construction of the
 outer side is identical, the bench being
 75 symmetrical on opposite sides of a central,
 longitudinal plane in this respect. The air
 flues of the units of regenerators 49 are
 marked 70, 71, 72 and those of the units of
 regenerator 50 are marked 73, 74, 75. The
 80 three flues from each regenerator open into
 a common duct or passage 76 (see Figs. 2
 and 12) which is provided with two branches
 77, 78, one of which 77, has an opening 79
 communicating with the open air and con-
 85 trolled by a valve 80 and the other 78 of
 which communicates with a stack flue 81 and
 is controlled by a damper or valve 82. The
 valves 80 and 82 of all of the regenerators
 may be operated independently or the valves
 90 of regenerators 49 coupled together and
 those of regenerators 50 coupled together
 for joint action in an obvious manner.

From the foregoing the operation of the
 construction will be readily grasped. Prefer-
 ably the flow of gases is in the same direc-
 95 tion in all of the heating chambers at the
 same time and is simultaneously reversed.
 When the flow of gases is upward in the
 heating chambers the valves 80 controlling
 the admission of air to regenerators 49 are
 100 open and the dampers 82 controlling connec-
 tion thereof to the stack flue closed, while
 the valves 80 in the passages opening from
 regenerators 50 to the air are closed and the
 dampers 82 connecting the last mentioned
 105 regenerators with the stack flue are open.
 At the same time fuel gas is supplied to the
 lower ignition chambers and the inter-
 mediate ports and shut off from the upper
 ignition chambers. Air then flows through
 110 the heated chambers of regenerators 49 to
 the lower ignition chambers where it meets
 jets of gas from the mains. The products
 of combustion formed flow vertically up-
 ward through the heat absorption zones in
 115 termediate of which their temperature is
 again raised by the combustion of gas sup-
 plied through the intermediate ports. The
 products of combustion escape through the
 upper ignition chambers and the ports there-
 of and pass downwardly through flues 57
 120 and regenerators 50, which latter extract
 heat therefrom, and thence through the re-
 generator flues to the stack flue. When the
 flow is reversed after a suitable interval the
 air for supporting combustion passes
 125 through regenerators 50 and meets jets of
 gas in the upper combustion chambers, the
 products of combustion then flowing down-
 ward through the heat absorption zone to
 the lower ignition chambers and thence
 through the regenerators 49 and to the stack
 flue. The supplemental or intermediate
 combustion midway the heat absorption zone
 takes place with the flow in either direction,

fuel gas being supplied at all times for this purpose.

In my improved construction of coke oven the heating walls in contact with the charges within the coking chambers are uniformly heated throughout, the reversal of flow coupled with the secondary combustion providing substantial uniformity throughout in a vertical direction and the independent heating and supply of air to the respective ignition chambers insuring even distribution of the air throughout the length of the wall, while the vertical diaphragms in the heating chambers prevent the concentration of hot gases due to lateral movement thereof without substantially interrupting the continuity of the heat-absorbing wall of the heating chamber. By reason of the uniformity of heat distribution the temperature of all parts of the wall may be raised to the point most desirable for practical coking operation, the high temperature coupled with the even heat distribution producing a uniform high grade coke and permitting the manufacture of a satisfactory metallurgical coke from coals which have heretofore been unsatisfactory for the purpose.

I claim:

1. A series of horizontally elongated coking chambers arranged side by side, the intermediate walls thereof being common to each two contiguous chambers respectively, each heating wall having heating chambers on opposite sides of the central plane thereof, ignition chambers at the top and bottom respectively of the heating chambers, ports for conveying air to and waste gases from the lower ignition chambers, vertical passages intermediate the heating chambers and communicating with the lower ends thereof for supplying them with fuel gases, mains supplying the upper ends of said passages with fuel gases, other vertical passages extending between the heating chambers and opening thereinto intermediate their height, mains for supplying gas to the last named passages, ports communicating with the upper ignition chambers for supplying air thereto and permitting the escape of waste gases therefrom and vertical flues intermediate the heating chambers and communicating with the last named ports on opposite sides of the wall.

2. A series of horizontally elongated coking chambers arranged side by side, the intermediate walls thereof being common to each two contiguous chambers respectively, heating chambers in said walls on opposite sides of the central planes thereof, passages for supplying fuel gas to the upper ends of the heating chambers, regenerators parallel to and below the heating walls, each divided by transverse vertical walls into a series of independent elements, vertical flues extending upwardly from the respective said ele-

ments between the heating chambers in the walls, and ports connecting some of said flues at their upper ends to the heating chambers on one side thereof, and ports connecting the upper ends of the other flues to the upper ends of the heating chambers on the other side thereof.

3. A series of horizontally elongated coking chambers arranged side by side, the intermediate walls thereof being common to each two contiguous chambers respectively, heating chambers on opposite sides of the central planes of the heating walls, means for supplying fuel gas to the upper and lower ends of the heating chambers, regenerators arranged parallel to and immediately below the respective coking chambers, ports and passages connecting said regenerators with the lower ends of the heating chambers on opposite sides of the coking chamber immediately above said regenerator, intermediate regenerators immediately below the respective heating walls, flues and ports connecting the intermediate regenerators to the upper ends of the heating chambers in the walls immediately above said regenerators and vertical partitions dividing said regenerators and heating chambers into corresponding longitudinal sections.

4. A series of horizontally elongated coking chambers arranged side by side, the intermediate walls thereof being common to each two contiguous chambers respectively, heating chambers on opposite sides of the central planes of the respective heating walls, vertical transverse partitions dividing the heating chamber into a series of divisions, a series of upper and lower ignition chambers in each heating chamber division, a series of regenerators parallel to and directly below the respective coking chambers, vertical walls dividing such regenerators into elements, passages connecting alternate said elements with a lower ignition chamber on one side of the coking chamber respectively immediately above the same, passages connecting intermediate said elements with an ignition chamber on the other side of said coking chamber, a series of regenerators parallel to and directly below the respective heating walls and intermediate the regenerators of the first said series, walls dividing each said regenerator into a series of heating elements, passages connecting alternate said heating elements respectively with upper ignition chambers at the one side of said wall, passages connecting intermediate elements of said regenerators respectively with upper ignition chambers in the other side of the said wall, and means for supplying fuel gas to the upper and lower ignition chambers.

5. In a bench of coke ovens a series of parallel coking chambers, a pair of combustion chambers arranged respectively on op-

- posite sides of each coking chamber, burners for supplying fuel gas at the top and bottom of each combustion chamber, a series of regenerators arranged beneath the respective 5 coking chambers, each regenerator divided into pairs of regenerative sections, one member of each pair connected to the combustion chamber on one side of the respective coking chamber and the other member of each pair connected to the combustion chamber on the other side of said coking chamber, intermediate regenerators and connections therefrom to the upper ends of the combustion chambers.
- 10 6. In a coke oven a series of parallel coking chambers, a pair of combustion heating chambers for each coking chamber arranged respectively on opposite sides thereof, gas ports and passages for supplying fuel gas 20 to the upper and lower ends respectively of each combustion chamber, a regenerator arranged beneath each coking chamber and divided into groups of four sections each by transverse walls therein, connections from 25 alternate members of each group to the lower end of one of said combustion chambers, connections from intermediate sections to the lower end of the other of said combustion chambers, and means for supplying air to the upper ends of said combustion chambers.
7. In a coke oven a series of parallel coking chambers, a plurality of combustion chambers on each side of each coking chamber in the intermediate walls, a regenerator beneath the coking chamber divided into units, there being a plurality of pairs of elements in each unit, connections from one member of each pair to the lower end of 40 the corresponding combustion chamber on one side of the coking chamber, connections from the other member of each pair to the lower end of the similar combustion chamber on the other side of said coking chamber, means for supplying air to the upper ends of said combustion chambers, and means for supplying gas to the upper and lower ends thereof.
8. A series of horizontally elongated coking chambers arranged side by side, the intermediate walls thereof being common to each two contiguous chambers respectively, a pair of combustion chambers in each wall, ports and passages for supplying fuel gas 55 to the upper and lower ends of said combustion chambers, a regenerator beneath each coking chamber and comprising a plurality of pairs of regenerator sections, connections from a member of each pair of sections to the lower end of the combustion chamber on one side of the coking chamber, connections from the other member of each pair to the lower end of the combustion chamber on the other side of said coking chamber, regenerators intermediate the first-mentioned re-
- generators and respectively beneath the partition walls, division walls dividing each of said last named regenerators into a plurality of sections, air flues extending from the last said sections vertically upward through 70 the walls intermediate the combustion chambers therein, and connections from the upper ends of said air flues to the upper ends of the combustion chambers.
9. A series of horizontally elongated coking chambers arranged side by side, the intermediate walls thereof being common to each two contiguous chambers respectively, each having a pair of heating chambers extending substantially the length thereof, vertical partitions dividing said chambers into a series of independent heating chambers, a series of ignition chambers along the top and bottom respectively of each said divisional heating chamber, means for supplying fuel 80 gas to said ignition chambers, regenerators arranged respectively beneath the coking chambers and parallel thereto, regenerators arranged respectively beneath the heating walls, vertical partitions dividing the regenerators into units, vertical partitions dividing each unit into pairs of elements, connections from one element of each of said pairs of elements of each regenerator beneath a coking chamber to the lower end of 85 a heating chamber on one side of said coking chamber, connections from the other element of such pair to the lower end of the heating chamber on the other side of said coking chamber, and connections from the respective said elements of the regenerators arranged beneath the respective heating walls to the upper ends of the heating chambers in said walls.
10. A series of horizontally elongated coking chambers arranged side by side, the intermediate walls thereof being common to each two contiguous chambers respectively, heating chambers in the heating walls, ports for admitting air to the lower ends of the 100 heating chambers, upwardly opening ports for admitting fuel gas to the lower ends of the heating chambers, vertical passages in the walls, means for supplying said passages at their upper ends with gas, inclined 105 ducts connecting the lower ends of said passages with said upwardly opening ports, horizontal passages beneath said ports and into which the lower ends of said ports open, said horizontal passages being open at their ends for cleaning and valves for normally closing the connection between said ports and horizontal passages.
11. A series of horizontally elongated coking chambers arranged side by side, the intermediate walls thereof being common to each two contiguous chambers respectively, a pair of heating chambers in each wall on opposite sides of the central plane thereof, regenerators arranged beneath and parallel 120 125 130

to said chambers and walls, there being a regenerator beneath each coking chamber and beneath each wall, transverse vertical walls completely dividing said heating chambers, vertical walls in substantially the same plane as the last said walls dividing the regenerators into units, connections from

the units of alternate regenerators to the tops of a corresponding division of the heating chamber, and connections from the units of intermediate regenerators to the bottoms of the corresponding divisions of the heating chambers. 10

THOMAS G. KUS.
